UNITED STATES PATENT OFFICE.

WILLIAM C. NASH, OF MENASHA, WISCONSIN.

NOISELESS STRAINER.

1,200,127.

Specification of Letters Patent. Patented Oct. 3, 1916.

Application filed July 12, 1916. Serial No. 108,876.

To all whom it may concern:

Be it known that I, WILLIAM C. NASH, a citizen of the United States, residing at Menasha, in the county of Winnebago and 5 State of Wisconsin, have invented certain new and useful Improvements in Noiseless Strainers, of which the following is a specification.

This invention relates to strainers, and 10 more particularly to devices of this nature as used in the manufacture of pulp and like materials for use in making paper and other manufactured products, which strainers are known to those skilled in the art as pulp 15 screens.

An object of my invention is to provide means by which a pulsating circulating impulse is given to the water or other liquid having the fiber in suspension so that this 20 fiber will be broken up to give a more pulpy and homogeneous consistency to the entire mass, and to so construct this impulse giving means that the screen of the strainer will be cleaned and any large particles 25 which may lodge thereon will be thrown back into the semi-liquid or liquid mass to be further beaten and separated by the pulsating movement until the particles of the comminuted material making up the pulp 30 are all sufficiently finally divided and separated that they will pass through the screen.

A further object is to so construct the 35 means by which the pulsating movement is given that the vibration of the diaphragm or other means by which the pulsating impulses are given to the liquid body is actuated by the use of compressed air or other fluid pressure and thus permits regulation of the pressure thereby allowing adjustment and variations in the action for particular masses of material being treated and insuring a cleaner sheet of paper or a cleaner manufactured product and less accumulation of lumps.

45 A still further object lies in providing a fluid actuated operating means which is capable of working to attain a relatively great number of impulses in a short period and which is economical in its use of fluid 50 as a minimum quantity of fluid is required for each impulse.

With the above and other objects in view, my invention consists in certain novel features of construction and combinations of 55 parts which will be hereinafter set forth in

connection with the drawings and then more particularly pointed out in the claims.

In the drawings:—Figure 1 is a view in elevation of a strainer with my invention applied thereto and with parts shown in 60 section to more clearly illustrate the co-operating elements. Fig. 2 is an enlarged detail sectional view showing the fluid actuated means. Fig. 3 is a transverse sectional view taken on the line 3—3 of Fig. 2.

The chamber 1 is provided to receive the pulp which is connected with a proper proportion of liquid, and this chamber has a false bottom which is made in the form of 65 perforated plates 2, these plates constituting 70 the strainer section and being either perforated with a plurality of fine openings or provided with relatively narrow slits or slotted openings therethrough. The screen 75 sections or the perforated plates 2 are preferably made so that they can be fitted in a relation that a plurality of the various plates will form the completed bottom for the chamber 1, the cross bars 3 being provided to support these plates 2, and as certain of 80 the cross bars more particularly designated by the reference character 4 are extended to have bearing against the bottom portion 5 of the main structure, a plurality of separate 85 receiving chambers are provided beneath the first mentioned chamber and below the plates.

The bottom portion 5 is supported on suitable legs or standards 6 and 7 so that it is disposed substantially horizontally, and this 90 bottom constitutes the cross bars which are spaced apart to leave openings 8 therebetween. The depressed outlet passages 9 are formed in the portion 5 adjacent to the cross bars 4 which provide the separate receiving 95 chambers 10 one from the other. The diaphragms 11, which are of sheet rubber or other suitable material are secured across the openings 8 and on the upper side of the bottom portion 5 so that they provide closures for the bottoms of the separate receiving chambers 10. A hollow shaft 12 is connected across between the standards 6 and 7 to be thus disposed longitudinally of the machine and is positioned preferably centrally beneath the openings 8, a belt pulley 13 being connected on this hollow shaft 12 to permit the application of power to turn the same. A compressed air pipe or fluid supply pipe 14 is led from any suitable 100 105

source of supply of fluid under pressure and is connected to a stuffing box 15 with the hollow shaft 12, a valve 16 being provided to control the passage of fluid through this 5 pipe 14.

Operating rods or stems 17 are connected through suitable bearing members 18 to be capable of reciprocatory movement and at their upper ends have the head portions 19 10 shaped to have a reasonably snug fit in the openings 8 and to present a broad flat surface against the under side of the flexible diaphragm 11, one of these operating rods or stems being mounted beneath each of the 15 diaphragms. Bearing casings 20 are mounted at spaced apart points around the hollow shaft 12 and are provided with side extensions 21 having the fluid passages 22 therethrough from the bearing openings. A 20 cylinder casing 23 is mounted around this extension 21 of each of the bearing casings 20 and the extension has a snug sliding fit with the cylinder so that it acts as a piston. The upper end of the cylinder 23 is bored 25 centrally and this bore is made sufficiently large that the rod or stem 17 of the adjacent diaphragm pulsating structure is received at its lower end in this bore, the adjusting nut 24 being provided on the screw threaded 30 lower end of each of the stems to permit adjustment of the operating rods or stems 17 and to consequently vary the relative setting of the head 19, the set nut 25 being received on the screw threaded end of the 35 rods 17 to tighten down against the adjusting nut 24 and to thus hold the adjustment.

The slide bearing rods 26 and 27 are secured on the bearing casing 20 on each side of the extension 21 and at their upper ends 40 are screw threaded. The cylinder 23 is provided on opposite sides with the ears or lugs 28 and 29, and these lugs are bored through to provide bearing openings to be loosely fitted on the slide bearing rods 26 45 and 27, coil springs 30 and 31 being mounted around the bearing rods 26 and 27 above these bearing ears 28 and 29 and the adjusting nuts 32 are provided on the screw threaded end of the bearing rods 26 and 50 27 to permit adjustment of the tension of the springs 30 and 31, lock nuts 33 being provided to tighten against these adjusting nuts 32 and to thus hold the same against displacement due to the constant vibratory or pulsating movement which is imparted to the parts as will be hereinafter set forth.

With the parts arranged as is above set forth, the springs 30 and 31 of each set of diaphragm actuating parts will normally act 60 to exert tension against the ears 28 and 29 to bring the corresponding cylinder 23 down to a point that the inner end of the bore thereof rests against the head end of the extension 21 of the corresponding bearing casing 20, 65 and thus the corresponding diaphragm 11

will be brought to the relation shown at the extreme right hand in Fig. 1 where it is substantially level with the lower portion 5 of the separate receiving chambers 10. It is advisable that this represent one extreme 70 position, and of course adjustment can be made through the nuts 24 and 25 to permit the attainment of a fine regulation to accomplish the proper positioning of the diaphragm. Packing rings 34 and 35 are 75 mounted around the shaft 12 adjacent to each end of each of the bearing casings 20 and these rings are preferably shaped to interfit with portions of the bearing casing 20 so that the bearing casings will be held 80 against displacement longitudinally of the shaft. The shaft 12 is provided with slits or air ports 36 formed therethrough at equally spaced apart points around its wall, and these slits or ports are positioned to 85 register with the port or passage 22 when the shaft 12 is turned. The groove 37 is formed in the outer wall of the shaft 12 adjacent to each of the ports 36 and these grooves are extended for a sufficient distance along the longitudinal extent of the shaft 12 that they open out at each end beyond the rings 34 and 35.

In the use of the device, the pulp together with the liquid will be placed in the chamber 95 1 by being slid through the pipe 38, or from any other suitable source, and the main body of the pulp will be held against passage through the screen plates 2 due to the fineness of the mesh of the same. Now as the 100 valve 16 is opened and fluid is supplied under pressure to the hollow shaft 12 and turning movement is transmitted to the same, the ports 36 will come into registry with the passage 22 and consequently as each of these 105 ports registers with the corresponding passage, fluid under pressure will be supplied to the respective cylinders and to the operating rods or stems 17 connected with the cylinders 23. The heads 19 will be raised to 110 distend the diaphragms 11 upwardly. As the shaft 12 continues in its rotation, the passage 22 will register with the next adjacent groove 37 and consequently the fluid under pressure within the cylinder will be 115 permitted to escape back through the passage 22 and through the groove 37 to exhaust into the atmosphere and the cylinder 23 will be again returned to the position of inaction through the medium of the springs 30 and 120 31. By positioning several ports around through the wall of the hollow shaft, a multiplicity of pulsating impulses will be imparted to each of the diaphragms upon each complete revolution of the shaft 12. It is 125 preferable that four, six, or more or less of the separate receiving chambers 10 be provided, and under these circumstances it will of course be understood that a corresponding number of bearing casings 20 to 130

gether with the connected parts will be mounted as part of the completed machine. As the pulp together with the liquid is contained in the chamber 1 and in the separate receiving chambers 10, this pulsating movement of the diaphragms 11 will cause alternate suction downwardly through and pressure upwardly in the separate receiving chambers and consequently through the screen plates 2, and thus the pulp fiber will be broken up and any lumps which may exist in the mass, and only those particles which are sufficiently small to pass the mesh of the screen plate will find their way into the separate receiving chambers 10 to subsequently pass therefrom through the depressed or sunken outlet passages 5. It is preferable that the parts be operated so that the diaphragms 11 will have approximately 440 impulses to the minute, and as a number of fluid supply ports are formed from the hollow shaft 12 in conjunction with each of the diaphragm vibrating means, it will of course be understood that the shaft need not run at a number of R. P. M. corresponding to the number of impulses desired but rather this can be of course mathematically calculated for the number of impulses given above or for any greater or lesser number. By varying the compression of the springs 30 and 31, the tension exerted by the same against the ears 28 and 29 of the cylinder 23 can be varied to give quicker or slower return movement and in the same way by increasing and decreasing the fluid pressure, the working strokes of the cylinders may be made sharper or more sluggish to suit various operating positions. Where a multiplicity of vibrating devices are fitted in conjunction with a single hollow shaft, it is preferable that the fluid supply ports of the various sets be staggered throughout the length of the shaft and thus all of the working impulses will not come at the same time and in this way the load upon the shaft will be equalized and distributed throughout the complete revolution thereof.

From the foregoing it will be seen that I have provided an operating structure by which a pulsating or vibratory movement is imparted, which structure is perhaps particularly well adapted for use in connection with a strainer such as is used for pulp screening and in other connections in paper making, and thus the device is so constructed that the outstroke is cushioned by the springs 30 and 31 while the return stroke under the tension of these springs is cushioned by the escaping air in the cylinder, and further it will be apparent that a device is provided which is at once very simple and efficient in its operation but at the same time is economical in its use of the compressed fluid. Further it will be noted that with such a structure as this there is not the

necessity for the use of cams or other mechanical operating means in consequence of which there is not the objectionable bumping following each rising stroke, the use of oil is minimized, the wear upon the parts is only such as will come to any turning or reciprocating part, and at the same time a more efficient operation is obtained and adjustment may be made to suit various operating conditions and to adapt the machine with which the actuating means is constructed so that the machine will operate with greater efficiency upon various conditions of material.

While I have herein shown and described only one specific form of the structure, it will be understood that various changes and modifications might be resorted to in the form and arrangement of the parts as well as in the application of the actuating mechanism without departing from the spirit and scope of my invention and hence I do not wish to be limited to the exact disclosure but only to such points as may be set forth in the claims.

I claim:

1. A revolvably mounted hollow shaft having grooves and ports therein, a bearing casing mounted around the grooved and ported portion of the shaft and having an extension provided from one side thereof with a passage through the extension, and a cylinder mounted in a sliding fit over the extension, the parts being so arranged that upon turning of the shaft an expansive fluid is supplied through the ports and the passage to the cylinder and is permitted to escape therefrom through the grooves.

2. A revolvably mounted hollow shaft having grooves and ports therein, a bearing casing mounted around the grooved and ported portion of the shaft and having an extension provided from one side thereof with a passage through the extension, a cylinder mounted in a sliding fit over the extension, the parts being so arranged that upon turning of the shaft an expansive fluid is supplied through the ports and the passage to the cylinder and is permitted to escape therefrom through the grooves, and means to yieldingly oppose the movement of the cylinder under the action of the expansive fluid supplied thereto and to return the same as the fluid is permitted to exhaust through the grooves.

3. A revolvably mounted hollow shaft having grooves and ports therein, a bearing casing mounted around the grooved and ported portion of the shaft and provided with an extension from one side having a passage therethrough, a cylinder mounted in a sliding fit over the extension, the parts being so arranged that upon turning of the shaft an expansive fluid is supplied through the ports and the passage to the cylinder to cause ex-

5 tension of the same along the length of the casing extension and is permitted to exhaust from the cylinder through the grooves, guide rods extended from the casing in line
5 with the extension thereof, portions extended from said cylinder to be received around the guide rods in a sliding fit, springs mounted on the guide rods to bear against the portions of the cylinder, and means by
10 which the tension of the spring may be adjusted to regulate the force exerted by the same in opposing expansion movement of the cylinder and in returning the same when the fluid is exhausted through the grooves.
15 4. In a strainer, the combination with a chamber having a horizontal perforated plate disposed as the bottom thereof to provide receiving chambers beneath the plate, flexible diaphragms forming the bottom of
20 said receiving chambers, operating rods having heads thereon mounted to be capable of movement to vibrate said diaphragms, a hollow shaft having grooves and ports therein revolvably mounted below said operating rod, a bearing casing mounted around the grooved and ported portion of the shaft in line with each of said rods, an extension provided from each of the casings and having a passage therethrough, a cylinder connected on the end of each of the operating rods and mounted in a sliding fit over the extension 35 of the adjacent bearing casing, the parts being so arranged that upon turning of the shaft an expansive fluid is supplied through the ports and the passages to the cylinders and is permitted to exhaust therefrom through the grooves thus giving the desired reciprocatory movement 40 to the operating rod.
45 5. In a strainer, the combination with a chamber having a horizontal perforated plate disposed as the bottom thereof to provide receiving chambers beneath the plate, flexible diaphragms forming the bottom of
50 said receiving chambers, operating rods having heads thereon mounted to be capable of movement to vibrate said diaphragms, a hollow shaft having grooves and ports therein revolvably mounted below said operating rod, a bearing casing mounted around the grooved and ported portion of the shaft in line with each of said rods, an extension provided from each of the casings and having a passage therethrough, a cylinder connected 55 on the end of each of the operating rods and mounted in a sliding fit over the extension of the adjacent bearing casing, the parts being so arranged that upon turning of the shaft an expansive fluid is supplied through
60 the ports and the passages to the cylinders and is permitted to exhaust therefrom through the grooves thus giving the desired reciprocatory movement to the operating rod, and means carried by the bearing casing arranged to resiliently oppose the extension

movement of the cylinders and to return the same upon the exhaust of the expansive fluid through the grooves.

6. In a strainer, the combination with a chamber having a horizontal perforated plate disposed as the bottom thereof to provide receiving chambers beneath the plate, flexible diaphragms forming the bottom of said receiving chambers, operating rods having heads thereon mounted to be capable of movement to vibrate said diaphragms, a hollow shaft having grooves and ports therein revolvably mounted below said operating rod, a bearing casing mounted around the grooved and ported portion of the shaft in 70 line with each of said rods, an extension provided from each of the casings and having a passage therethrough, a cylinder connected on the end of each of the operating rods and mounted in a sliding fit over the extension 75 of the adjacent bearing casing, the parts being so arranged that upon turning of the shaft an expansive fluid is supplied through the ports and the passages to the cylinders and is permitted to exhaust therefrom 80 through the grooves thus giving the desired reciprocatory movement to the operating rod, guide rods extended from said bearing casings on each side of the extensions thereof, portions extended from the cylinders to 85 be received in a sliding fit around each of the guide rods, springs mounted around the guide rods to bear against the extension portions of the cylinder, and means connected on the guide rods to adjust the tension of 90 said springs and to consequently vary the force exerted thereby against the portions of 95 the cylinder.

7. In a strainer, the combination with a chamber having a horizontal perforated 105 plate disposed as the bottom thereof to provide receiving chambers beneath the plate, flexible diaphragms forming the bottom of said receiving chambers, operating rods having heads thereon mounted to be capable of movement to vibrate said diaphragms, a hollow shaft having grooves and ports therein revolvably mounted below said operating rod, a bearing casing mounted around the grooved and ported portion of the shaft in 110 line with each of said rods, an extension provided from each of the casings and having a passage therethrough, a cylinder connected on the end of each of the operating rods and mounted in a sliding fit over the extension 115 of the adjacent bearing casing, the parts being so arranged that upon turning of the shaft an expansive fluid is supplied through the ports and the passages to the cylinders and is permitted to exhaust therefrom 120 through the grooves thus giving the desired reciprocatory movement to the operating rod, guide rods extended from said bearing casings on each side of the extensions thereof, portions extended from the 125

cylinders to be received in a sliding fit around each of the guide rods, springs mounted around the guide rods to bear against the extension portions of the cylinder, means connected on the guide rods to adjust the tension of said springs and to consequently vary the force exerted thereby against the portions of the cylinder, the ports and grooves in conjunction with the various bearing casings being arranged in staggered relation to distribute the load, and

adjustable means between the cylinders and the operating rods to permit setting of the rods to dispose the diaphragms at the proper height.

In testimony whereof I affix my signature in presence of two witnesses.
